ATTORNEYS

UNITED STATES PATENT OFFICE.

COURTLAND HAYNES, OF HAWESVILLE, KENTUCKY.

DESIGN FOR A DRAINER.

SPECIFICATION forming part of Design No. 31,491, dated September 5, 1899.

Application filed August 8, 1899. Serial No. 726,591. Term of patent 7 years.

To all whom it may concern:

Be it known that I, COURTLAND HAYNES, a citizen of the United States, residing at Hawesville, in the county of Hancock and State of Kentucky, have invented and produced a new and original Design for a Drainer, of which the following is a specification, reference being had to the accompanying drawings, forming a part thereof, in which—

Figure 1 is a plan view of a drainer embodying the features of my design, and Fig. 2 is a transverse section on the line 2 2 of Fig. 1.

The leading features of the design consist in the especial shape of the drainer, in which the bottom A is in the same horizontal plane throughout and the back B is a straight line from side to side, while the sides C are parallel and straight from the back B to a point near the front, from which point the sides

gradually converge and meet a straight line 20 D, defining the front of the drainer.

The minor features of the design consist of an upwardly-extending marginal rear and side flange e, which flange terminates at the front, and gutters F, following the line of the 25 side flanges, together with longitudinal gutters F', all of which extend forwardly from the rear flange, and sundry of said gutters F' connect with the side gutters F, others of the gutters F' extending to the front of the drainer. 30

I claim—

The design for a drainer herein shown and described.

COURTLAND HAYNES.
